UNITED STATES PATENT OFFICE.

JAMES LEVER RUSHTON, OF BOLTON, ENGLAND.

ARTIFICIAL-SILK AND LIKE SPINNING MACHINE.

Application filed September 15, 1926, Serial No. 135,645, and in Great Britain September 26, 1925.

This invention is for improvements in or relating to artificial silk and like spinning machines of the type having the filament directed into the spinning box by a funnel, 5 which is usually of glass, and which reaches into the interior of the spinning box and has to be removed therefrom when the spinning box is to be detached, or when the cake of artificial silk is removed, even if the box is 10 not detached; for this purpose the funnel is carried in a movable mounting which is adapted to support the funnel in its operative position and in an inoperative position in which it is clear of the spinning box, and 15 the mounting permits the funnel to be readily moved by a swinging or like movement between such positions without disturbing the setting of the funnel in the mounting. The invention has for one of its objects to provide 20 an improved construction of machine, of this type, in which the movement of the funnel to and from its operative position inside the spinning box is effected in a more convenient and efficient manner than has 25 heretofore been proposed.

According to the primary feature of the present invention there is provided a machine of the above type which is characterized in that the funnel mounting is so constructed and arranged in relation to the spinning box that the withdrawal movement 30 of the funnel from its operative position to a position outside the spinning box, and the return movement from the said outside position to operative position, are substantially in the direction along the length of the funnel spout or stem. Conveniently, the mounting is so constructed and arranged that subsequent to the said withdrawal movement 35 the funnel is moved clear of the spinning box in a direction laterally of the length of the funnel spout or stem. It will be appreciated that by the employment of the present invention the funnel is moved into and 40 out of its operative position readily and without risk of breakage, and that, furthermore, since its actual withdrawal movement from its operative position to a position outside the spinning box is substantially in the 45 direction along the length of the funnel spout, the aperture in the cover of the spinning box through which the stem has to pass can be made of dimensions closely approximating to those of the spout and conse-

quently the risk of acid splashing out of the 55 spinning box through this aperture is minimized.

The motion may be imparted to the funnel by various forms of mechanisms including levers and/or cams, but it is preferred to employ an articulated framework whereof one side is relatively stationary and the other sides move to carry the funnel to and from operative position relatively to the spinning box. The funnel may be carried 60 by a side of the framework which is connected by other sides to the aforesaid stationary side. In one construction the articulated framework comprises parallel motion sides whereof the pivots which are translated during the parallel motion lie at the 65 ends of a side which carries the funnel and also lie in a plane parallel to, or coincident with, the longitudinal axis of the funnel spout. This parallel motion framework affords a simple and compact mechanism for effecting the desired result. The mounting is preferably so disposed that when the funnel is in its operative position the movable 70 sides lie slightly to one side of the dead centre position in which opposite sides are furthest apart and through which dead centre position the sides move in withdrawing the funnel from the spinning box.

For a more complete understanding of the 75 invention there will now be described, by way of example only and with reference to the accompanying drawings, one constructional form of funnel-carrying mechanism according to the invention. It is to be understood, however, that the invention is not restricted to the precise constructional details set forth.

In these drawings:—

Figure 1 is a side elevation of the mechanism showing the parts in full lines in their operative position and in chain lines in their 85 fully withdrawn position, and

Figure 2 is an end elevation of the mechanism, partly in section, on the line 2—2 of 90 Figure 1.

Like reference numerals indicate like parts throughout the drawings.

In the drawings a portion of the centrifugal spinning box of an artificial silk spinning machine is illustrated at 10 and a cover therefor at 11. The traverse rail is shown 105 at 12 and it will be understood that there is

relative vertical reciprocation between the spinning box 10 and the traverse rail in order to lay the filament in a series of coils inside the spinning box. The mouth or intake portion of the funnel is indicated at 13 and the spout or stem thereof at 14, the latter being arranged vertically. The funnel is carried in an ebonite holder 15 which is threaded on its exterior and is loosely received in an aperture in a horizontal extension 16 from a vertical member 17. The holder and funnel are adjusted in position in the extension 16 by means of nuts 18 and 19, one of which is situated above and the other below the said extension. Mounted on the traverse rail 12 is a bracket 20, and the member 17 and bracket 20 are connected by two pairs of side members 21 and 22, and 23 and 24 respectively, the sides in the one pair being parallel to those in the other pair so that there is constituted an articulated framework consisting of the stationary bracket 20, the movable member 17 (which always remains vertical), and the parallel sides 21, 22, 23 and 24. At each of the joints there is a pivot pin 25 having an enlarged head 26 at one end and a reduced screw-threaded portion 27 at the other end which receives a securing nut 28. Under each nut there is a spring washer 29 and a plain washer 30 for providing the requisite amount of friction to retain the parts in any position in which they may be set, while at the same time only calling for a slight effort on the part of the operator to alter the setting. It will be seen that the two pivot pins 25 in the link 17 are situated vertically one above the other and likewise the two pivot pins 25 in the bracket 20 are situated one vertically above the other. The whole of the mechanism is preferably made of acid-resisting material.

It will be seen that when the parts are in the position shown in full lines in Figure 1, which is the operative position, the parallel sides 21, 22, 23 and 24 lie slightly below the horizontal position, namely the dead centre position in which the member 17 is furthest from the bracket 20. Obviously the parallel sides 21, 22, 23 and 24 have to pass through this dead centre position in passing to their completely withdrawn position which is illustrated in chain lines in Figure 1. There appears in Figure 1 an arc of a circle which indicates the path of movement of the point 31 at the lower end of the stem of the funnel. When this point has reached the position 32 it will be seen that it is clear of the spinning box and the cover and that in reaching this position it has experienced an amount of lateral displacement equal to the distance 33. The aperture 34 in the cover 11, therefore, has to accommodate this lateral displacement, but as such displacement is extremely small it will be appreciated that the aperture 34 can be kept quite small,

which is an important point in preventing acid from splashing out of the spinning box. In continuing its movement from the position 32 to the chain line position shown in Figure 1, the funnel is swept through an arc 70 which approaches more and more nearly to the horizontal and thus is carried clear laterally of the spinning box.

It is to be understood that the invention is not restricted to the precise constructional details set forth. For instance, it is not essential for the funnel to be maintained vertical in its withdrawn position; nor is it essential to employ a parallel motion framework.

I claim:—

1. In an artificial silk or like spinning machine of the type described, the combination with a funnel of a mounting therefor which is so constructed and arranged in relation to the spinning box that the withdrawal movement of the funnel from its operative position to a position outside the spinning box, is a continuous movement which, initially, is substantially in the direction along the length of the funnel and subsequently is in a direction laterally of the length of the funnel.

2. In an artificial silk or like spinning machine of the type described, a funnel mounting comprising an articulated framework whereof one side is relatively stationary and the other sides move to carry the funnel to and from operative position relatively to the spinning box, said framework being so situated relatively to the spinning box that the withdrawal movement of the funnel from its operative position to a position outside the spinning box is substantially in the direction along the length of the funnel and that subsequent to the said withdrawal movement the funnel is moved clear of the spinning box in a direction laterally of the length of the funnel.

3. In an artificial silk or like spinning machine of the type described, a funnel mounting comprising an articulated framework whereof one side carries the funnel, another side is relatively stationary, and further sides connect the two first-mentioned sides together, the said framework being so positioned in relation to the spinning box that the withdrawal movement of the funnel from its operative position to a position outside the spinning box is substantially in the direction along the length of the funnel, and that subsequent to the said withdrawal movement the funnel is moved clear of the spinning box in a direction laterally of the length of the funnel.

4. In an artificial silk or like spinning machine of the type described, a funnel mounting comprising an articulated framework whereof one side carries the funnel, and other sides, which have a parallel mo-

- tion, are pivoted to said funnel-carrying side by pivots which lie in a plane parallel to the longitudinal axis of the funnel.
5. In an artificial silk or like spinning machine of the type described, a funnel mounting comprising a four-sided articulated framework whereof one side carries the funnel, the opposite side is relatively stationary and the pivots connecting the 10 other pair of sides to the funnel-carrying side lie in a plane parallel to the longitudinal axis of the funnel.
6. In an artificial silk or like spinning machine of the type described, a funnel mounting comprising an articulated framework whereof one side is relatively stationary and the other sides move to carry the funnel to and from operative position in the spinning box, said framework being so 15 disposed relatively to the spinning box that when the funnel is in its operative position the movable sides of the framework lie
- slightly to one side of the dead centre position in which opposite sides are furthest apart, through which dead centre position 25 the sides move in withdrawing the funnel from the spinning box.
7. In an artificial silk or like spinning machine of the type described, an articulated funnel mounting which is so constructed and arranged in relation to the spinning box that movement of the mounting to withdraw the funnel from its operative position to a position outside the spinning box first causes movement of the funnel substantially 30 in the direction along the length of the funnel, and continued movement of the mounting causes the funnel to be moved clear of the spinning box in a direction laterally of 35 the length of the funnel.
- 40 In testimony whereof I affix my signature.

JAMES LEVER RUSHTON.
